UNITED STATES PATENT OFFICE.

ALBERT F. SPARKS, OF SPRINGFIELD, OHIO, ASSIGNOR TO THE JAMES LEFFEL & CO., OF SPRINGFIELD, OHIO, A CORPORATION OF OHIO.

WATER-WHEEL.

SPECIFICATION forming part of Letters Patent No. 783,761, dated February 28, 1905.

Application filed December 12, 1903. Serial No. 184,881.

To all whom it may concern:

Be it known that I, ALBERT F. SPARKS, a citizen of the United States, residing at Springfield, in the county of Clark and State of Ohio, have invented certain new and useful Improvements in Water-Wheels, of which the following is a specification, reference being had therein to the accompanying drawings.

This invention relates to water-wheels, and more specifically to water-wheels of the turbine type, particularly to the class of turbine-wheels which comprises a double wheel or, what amounts to the same thing, two wheels mounted on a single shaft or a plurality of coupled shafts, rotating in a vertical plane around a horizontal axis, having a double lateral discharge in opposite directions into separate draft-tubes. Heretofore in water-wheels of this class it has been found in practice that the vacuum in the upper portions of the two draft-tubes is frequently unequal, being greater in the one than in the other, thus producing a tendency to lateral movement of the wheel and a consequent end thrust of the shaft, which is obviously objectionable.

It is the object of my present invention to provide a construction whereby this objectionable end thrust may be avoided without impairing the efficiency of the turbine, the structure being such that an equal vacuum is maintained in both draft-tubes under all working conditions.

To this end my invention consists in combining with a structure of this class an equalizing pipe or conduit connecting the upper portions of the draft-tubes in such a way as to provide a free and unobstructed communication between them, thus insuring an equalizing of the vacuum in said tubes and a consequent absence of unbalanced side pressure on the wheel and end thrust of the shaft.

In the accompanying drawings, Figure 1 is a central vertical sectional view of a structure embodying my invention in one form, and Fig. 2 is a similar view of another of the numerous embodiments of which the invention is capable.

Referring first to the construction illustrated in Fig. 1, the reference-numeral 1

indicates a horizontal shaft upon which is 50 mounted a double wheel proper or runner 2, having a series of buckets 3 on each side of its central plane, which is vertical. This wheel is inclosed in a surrounding casing 4, into which the water is conducted in any suitable manner and from which it passes to the wheel through an annular inlet 5. The water after passing through the wheel or runner is in the present instance discharged laterally from both sides thereof through discharge-pipes 6, 55 the two parts of the discharge moving in opposite directions. The pipes 6 connect with elbows 7, which form the upper portions of the draft-tubes 8, lying on opposite sides of the wheel. The elbows 7 are preferably provided with stuffing-boxes 9 for the shaft 1. All of these parts may be of any approved construction and relative arrangement.

10 indicates an equalizing pipe or conduit connecting the upper portions of the two draft-tubes independently of the wheel or wheels. This conduit is free and unobstructed and preferably arises from the top of one of the elbows 7, passes over the casing 4, and then downward to a connection with the other elbow 7 at the top thereof. By means of this conduit the vacuum existing in the upper portions of the two draft-tubes is always maintained at an equality, so that there is never any excess pressure due to this cause on one side or the other of the wheel or runner and all end thrust of the shaft is done away with.

The construction just described in detail is manifestly only one of a number of forms in which the invention may be embodied, as it is applicable to any water-wheel mechanism where a plurality of wheels are mounted on a common shaft or connecting-shafting, said wheels having separate draft-tubes. The double wheel shown in Fig. 1 and just described may obviously be considered as two single wheels placed immediately adjacent to each other, and such immediate proximity of the wheels is in no way essential to my invention, as will be seen from a consideration of the structure shown in Fig. 2, in which the construction is identical in its main features with that already described, except that in

stead of the double wheel 2 two single wheels 11 are employed, discharging in opposite directions, as before, so as to balance each other. In both of the constructions shown the wheels 5 are inclosed in a single casing; but it is obvious that a separate casing for each wheel may be employed and that the position of the draft-tubes relatively to the wheels may be varied as desired; nor is the invention restricted 10 in its application to two wheels or its equivalent, a double wheel. I further wish it understood that the term "draft-tube" is employed by me in the description and claims herein in its broadest form, including therein 15 all of the discharge-conduit that receives the water from the wheel, beginning at the wheel. I therefore wish it to be distinctly understood that my invention is not limited to the two particular forms or arrangements of water-wheel mechanism shown, and it is, moreover, obvious 20 that my invention is not limited to the particular details of construction shown and described.

Heretofore in structures of the class to which 25 my invention relates where a double runner or wheel has been employed it has been the practice, where the wheel is of a sufficient diameter in proportion to the amount of water passing through it, to equalize the vacuum on 30 the two sides of the wheel by forming a passage through the hub or central portion of the wheel, and where the conditions are such as to the proportions between the diameter and discharge of the wheel that the discharge-wa- 35 ter does not obstruct this communicating passage. Equalization of the vacuum may be thus obtained through the wheel; but in the case of a double wheel, where these conditions do not obtain, it is found in practice that the volume 40 of the discharge-water, the space occupied by it, and at other times other factors result in so obstructing any passage or passages which may be formed through the wheel itself as to prevent the same from acting as an equalizing-conduit. It will be observed that in the 45 construction which I have devised the equalizing-conduit is entirely independent of the wheel and does not pass through the wheel, but around the same, being entirely external as 50 to the wheel. It will also be observed that where the wheels are located at separated points the employment of a passage or pas-

sages through the wheel is impracticable. By the employment of a vacuum-equalizing conduit which is independent of the wheel or 55 wheels and external relatively thereto I provide a means for equalizing the vacuum under all conditions.

Having thus fully described my invention, what I claim as new, and desire to secure by 60 Letters Patent, is—

1. The combination, with a plurality of water wheels or runners, a common horizontal shaft on which said wheels are mounted, and separate draft-tubes for said wheels, of a vacuum-equalizing conduit connecting the upper 65 portions of said draft-tubes independently of the wheels, substantially as described.

2. The combination with two water-wheels discharging laterally in opposite directions, 70 an inclosing supply-casing, and a common horizontal shaft on which both wheels are mounted, of separate draft-tubes, one for each wheel, and a vacuum-equalizing conduit connecting the upper portions of said draft-tubes inde- 75 pendently of the wheels, substantially as described.

3. The combination, with a double water-wheel discharging in opposite directions, a supply-casing inclosing said wheel, and a horizontal shaft on which said wheel is mounted, 80 of a separate draft-tube for each discharge of said wheel, and a vacuum-equalizing pipe connecting the upper portions of said draft-tubes independently of the wheel, substantially as 85 described.

4. The combination, with a double water-wheel discharging in opposite directions, a supply-casing inclosing said wheel, and a horizontal shaft on which said wheel is mounted, 90 of a separate draft-tube for each discharge of said wheel, each draft-tube comprising an elbow at its upper end connecting the body of the tube with the corresponding discharge, and a vacuum-equalizing pipe connecting the 95 said elbows independently of the wheel, substantially as described.

In testimony whereof I affix my signature in presence of two witnesses.

ALBERT F. SPARKS.
